HOOD MOUNTED AIR ACTUATED AUTOMOTIVE
SPEEDOMETER OR A SIMILAR ARTICLE

Thomas P. Brodick, 627 Fairfield Ave., Lombard, Ill.

Filed Sept. 16, 1964, Ser. No. 81,754

Term of patent 7 years

(Cl. D52—6)

FIGURE 1 is a perspective view of a hood mounted air actuated automotive speedometer, or a similar article, showing my new design;

FIGURE 2 is a front elevational view;

FIGURE 3 is a top plan view; and

FIGURES 4 and 5 are side elevational views from opposite sides.

I claim:

The ornamental design for a hood mounted air actuated automotive speedometer or a similar article, substantially as shown.
